UNITED STATES PATENT OFFICE.

THOMAS H. AMBROSE, OF PORT HOPE, ONTARIO, CANADA.

CAR-COUPING.

SPECIFICATION forming part of Letters Patent No. 279,307, dated June 12, 1883.

Application filed March 5, 1883. (No model.)

To all whom it may concern:

Be it known that I, THOMAS HITCHCOCK AMBROSE, of the town of Port Hope, in the county of Durham, in the Province of Ontario, Canada, have invented certain new and useful 5 Improvements in Car-Couplers, of which the following is a specification.

The object of this invention is to provide a simply and cheaply constructed car-coupler, so arranged that an ordinary coupling link and pin may be used when a car with my self-acting coupler is to be connected to a car having an ordinary draw-head; and it consists, essentially, in pivoting upon one side of the 15 draw-head a hook-shaped coupler having a weighted end and shaped to fit over a projection formed on the side of the coupler opposite to it.

Figure 1 is a plan of two draw-heads provided with my improved hooked coupler, one draw-head being shown in section, so as to indicate the formation of the recessed projection arranged to receive the flange formed on the boss on the pivot end of the coupler. Fig. 1^a 25 shows the pin cast on the coupler. Fig. 2 is an elevation of the draw-head, showing the hooked coupler. Fig. 3 is a sectional elevation of a draw-head attached to a car, and showing the coupler hooked up in the position it 30 will be held in when the draw-head is to be used with an ordinary link.

A are the draw-heads, constructed in the ordinary manner, except in the points herein-after specified.

35 B is a projection cast or otherwise formed on one side of the draw-head, and shaped, substantially as shown in Fig. 2, with its upper surface on an incline of about forty-five degrees, (45°), so as to permit the easy ascent of 40 the hooked end of the coupler C. This coupler C is pivoted on a pin, D, cast or otherwise formed on the side of the coupler opposite to that upon which the projection B is located. It will be noticed that the hooked end of the 45 coupler C has a swell, a, formed on its side, so as to weight the said end, in order to make it latch quickly the moment its hooked point has passed over the top edge of the projection B.

E is a projection formed on the side of the 50 coupler, on which the pin D is located. This

projection is recessed, as indicated in Fig. 2, so as to receive the flange b, formed on the boss of the pivot end of the coupler C. The flange, thus fitting into the recess, holds the coupler C on the pin D, while the projection E, within 55 which the recess is made, forms a strengthening-piece to assist the pin D in withstanding the strain exerted on the coupler.

F is a projection formed on the same side of the draw-head upon which the pin D and projection E are located. This projection extends below the bottom edge of the coupler C in such a position that the coupler C will be supported by it in about a horizontal position.

It will be noticed on reference to Fig. 1 that 65 the coupler C is pivoted on one side of one draw-head, while it is pivoted on the opposite side of the other draw-head, the projections B being likewise reversed on the two couplers. This change of location it will be seen is arranged for the purpose of permitting the couplers to connect when the draw-heads come together, the projections F on each draw-head 70 supporting its particular coupler in such a position that when the draw-heads approach each 75 other the couplers C latch over their respective projections B, and the desired connection is thus formed, as shown in Figs. 1 and 3.

When a car provided with my automatic coupler is to be connected to a car provided 80 with an ordinary draw-head, the usual link, G, and coupling-link H (see Fig. 3) may be used. When so used, the coupler C must of course be held out of the way, to accomplish which I form on the end of the coupler C a notch, d, 85 into which notch a link, e, may be fitted, the said link being attached, as shown in Fig. 3, to the end of a car.

I do not claim, broadly, a hooked coupler for the purpose of connecting together the draw- 90 heads of a car; but

What I do claim as my invention is—

1. In combination with coupling-hooks C, arranged reversely and having inclined portions a and flanges b, the draw-heads A, having pins D, recesses to receive said flanges b, and inclined lugs B, as and for the purposes set forth.

2. In combination with the draw-heads A and coupling-hooks C, as described, the links 100

e, adapted to engage the catches *d* of the hooks and hold them elevated, whereby an ordinary coupling-link, *G*, may be used, as set forth.

3. In a ear-coupling, and in combination with 5 a draw-head, having a pin, *D*, and portion *E*, cast with a recess, as shown, a coupling-hook, *C*, having a socket to receive said pin *D*, and a flange, *b*, fitting in the recess in the part *E*, whereby the link is held in operative posi-

tion by said flange and may be released by rotating the hook on the pin until the flange is disengaged, as specified.

Toronto, February 23, 1883.

THOMAS H. AMBROSE.
